UNITED STATES PATENT OFFICE.

JUSTUS W. FRENCH, OF LYNN, MASSACHUSETTS.

BOOT OR SHOE.

SPECIFICATION forming part of Letters Patent No. 392,264, dated November 6, 1888.

Application filed May 22, 1888. Serial No. 274,634. (No model.)

To all whom it may concern:

Be it known that I, JUSTUS W. FRENCH, of Lynn, in the county of Essex and State of Massachusetts, have invented an Improvement 5 in Boots or Shoes, of which the following description, in connection with the accompanying drawings, is a specification, like letters on the drawings representing like parts.

This invention has for its object an improved 10 construction of shoe, whereby the same may be cheaply lasted without the employment of tacks in the ball of the inner sole.

In accordance with my invention a lasting-sole narrower than the bottom of the last at 15 the ball thereof is employed instead and to take the place of the usual inner sole, the said lasting-sole having its edges immediately along the ball of the foot and between the toe portion, and the shank reduced in width and provided with a lip which points toward the center line of the sole, the said sole thus presenting along the ball abutting edges which fall within the side lines of the bottom of the last, and against which the upper is drawn by 20 stitches, the narrow portion of the lasting-sole having a groove, lip, or channel inside its abutting edges. When connecting the upper to the lasting-sole, the needle of any usual turn-shoe or welt-shoe sewing-machine will be 25 made to enter the channel or under the lip of the lasting-sole, the point of the needle emerging from the abutting edges and entering the upper, so that when the needle is drawn back to finish the stitch the thread will draw the 30 upper over the bottom of the last directly against the said abutting edge, thus connecting the upper with the lasting-sole at the abutting edge rather than with the outer side of the said sole. In this way the upper is 35 drawn and strained over the bottom of the last, and thereafter (the last having been withdrawn and the outer sole applied to the lasted shoe in usual manner) that portion of the upper lying between the abutting edge of the 40 lasting-sole and the edge of the last serves to receive the fastenings employed to unite the upper and outer sole, the said fastenings not entering the lasting-sole where it is reduced in width or between the portion thereof where 45 the upper was stitched to it, as described.

My invention therefore consists, essentially,

in a boot or shoe consisting of an upper and lasting-sole cut and reduced in width along the ball portion thereof between the toe and shank portions, and having a lip and an abutting edge located within the line of the bottom of the last in the direction of its width, the said upper being drawn against and stitched to the said abutting edges along only the ball of the shoe, and an outer sole united to the upper by a line of fastenings which pass through and through the outer sole, the upper, and the inner sole about the toe of the shoe and along the shank thereof, the said fastenings employed to secure the outer sole 55 in place passing through the upper and not through the lasting-sole along the ball of the shoe, substantially as described.

Figure 1 in side elevation represents a shoe embodying my invention; Fig. 2, a section in 70 the dotted line x ; Fig. 3, an under side view of the shoe, the upper along one side of the shoe being shown as lasted and trimmed, while at the opposite side of the shoe the upper is in position to be stitched to the lasting-sole, a part 75 of the upper being broken out to show the edge of the lasting-sole lying inside the edge of the last; Fig. 3^a, a section in the line x^a . Fig. 4 shows the lasting-sole by itself; Fig. 5, a section in the line x^b , with a piece of the upper in 80 place, the figure showing the needle in place and part of the last.

The upper a is and may be of usual shape and material.

The lasting-sole b will preferably be a piece 85 of leather reduced in width at and along the ball of the sole between the toe portion and shank portion, the lasting-sole herein shown having an inturned lip, b' , under which is a channel or groove. The lip b' is herein represented as formed upon the lasting-sole by slitting the latter from its opposite edge crosswise and transversely at four points, two at each side of the lasting-sole, between the toe portion b^{10} and shank portion b^{12} , the portion of the 90 sole between the parts where it is cut being bent over upon the face of the said sole, thus leaving an inturned lip.

The point of the needle employed to unite the upper to the lasting-sole emerges from the 100 upper and enters the lasting-sole at the abutting edge b^2 thereof—the edge left by reducing

the width of the sole along the ball portion—the point of the needle coming out through the said sole under the lip or flap b' , so that when the needle is drawn back to its starting-point 5 to finish the stitch the thread entering the upper and sole will act to draw the upper close to the said edge b^2 , or about the upper against the said edge at a point within the edge of the last, the upper being drawn and strained over 10 the last. As the upper is drawn up and secured to the edges b^2 , rather than drawn over and secured to the top of the sole, as has heretofore been done in welted work, I shall denominate the edge b^2 as the "abutting" edge.

15 In practice, the lasting-sole having been applied to the bottom of the last, the upper is drawn, by pinchers or otherwise, up to and over the edge of the last at the toe and through the shank and heel, when it may be temporarily 20 secured or caught in usual manner by tacks or nails 2, and then the upper is stitched to the abutting edge of the lasting-sole by a line of stitches. (Shown at 3, Figs. 2 and 3^a.)

For the work I may employ any sewing-machine commonly used to stitch the upper to the inner sole in welted work, or to stitch the upper to the outer sole for turned work, the stitch being either a chain or two-threaded stitch, as may be desired.

30 In Fig. 3 the upper side or half of the shoe is shown as stitched and the lip and edge of the upper trimmed off from the center of the toe to the shank; but along the other side of the shoe the upper is shown as yet held 35 by the tacks 2 in the last in position to be stitched.

The upper having been stitched to the abutting edge of the lasting sole, the nails 2 are withdrawn, the edge of the upper and the 40 edge of the lip b' projecting beyond the line of stitching are cut off nearly down to the said stitching, an outer sole, c , is applied to the shoe, the last is withdrawn, and the shoe is applied to the horn of a machine of usual 45 construction for uniting the sole and upper, and a line of fastenings, 4, preferably stitches, is put into the outer sole and upper outside the junction of the upper with the lasting

sole, as shown in Fig. 2; but the said stitches 4 pass through and through the lasting-sole 50 in the direction of its thickness both around the toe and through the shank, as in usual so-called "McKay work." In this way nails or tacks are not left in the ball of the shoe, nor is the chain of stitches uniting the upper 55 and lasting sole exposed at the inner side of the shoe. The cap will be nailed to the toe portion of the lasting-sole in usual manner.

A sock-sole will be applied in usual manner to the completed shoe, and the heel part of the 60 shoe and upper may be put together in any usual manner.

I do not broadly claim an inner sole having its edge cut away about the ball of the shoe, so that the stitching uniting the inner sole and 65 upper will run off the inner sole to thus make a flexible sole; but I am not aware that a sole of the shape referred to has ever been provided with a lip, as b' , to which the upper has been united for the purpose of lasting the shoe, 70 as herein described.

I claim—

The herein-described shoe, it consisting of an upper and lasting sole cut and reduced in width along the ball portion thereof between 75 the toe and shank portion, and having a lip, b' , and an abutting edge, b^2 , located within the edge of the line of the last in the direction of its width, the said upper being drawn against and stitched to the said abutting edges b^2 along 80 only the ball of the shoe, and an outer sole united to the upper by a line of fastenings which pass through and through the outer sole, the upper and inner sole about the toe of the shoe and along the shank thereof, the said fastenings employed to secure the outer sole in place passing through the upper and not through the lasting sole along the ball of the shoe, all substantially as described.

In testimony whereof I have signed my name 90 to this specification in the presence of two subscribing witnesses.

JUSTUS W. FRENCH.
